UNITED STATES PATENT OFFICE.

WILLIAM A. SHAW, OF MANCHESTER, COUNTY OF LANCASTER, ENGLAND.

DEVICE FOR RULING PARALLEL LINES.

SPECIFICATION forming part of Letters Patent No. 423,823, dated March 18, 1890.

Application filed July 1, 1889. Serial No. 316,170. (No model.) Patented in England January 8, 1889, No. 365.

To all whom it may concern:

Be it known that I, WILLIAM A. SHAW, of Stanley Mount, Ashton-under-Lyne, Manchester, in the county of Lancaster, Kingdom of Great Britain, have invented certain new and useful Improvements in Apparatus for Ruling Parallel Lines, (for which English Patent, No. 365, dated January 8, 1889, has been granted;) and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to certain improvements in devices for ruling straight parallel lines.

The object of the invention is to provide a simple, cheap, and yet durable and effective device for ruling parallel lines on paper or the like, which will be small and compact, self-inking, and easily operated by hand and always ready for use, can be carried in the pocket, can be adjusted to simultaneously rule any number of parallel lines, and is especially adapted for use by musicians and others in marking the "staff" upon which to write musical notes or characters. These objects are accomplished by, and my invention consists in, certain novel features of construction and combinations of parts more fully described hereinafter, and particularly pointed out in the claims.

Referring to the accompanying drawings, Figure 1 is a plan view of the hand-ruling device, the ruling-disks of which are adjustable to vary the number of and distance between the parallel lines ruled. Fig. 2 is a section of the same. Fig. 3 is a plan of the article adapted to rule a fixed number of parallel lines. Fig. 4 is a similar view of the same, showing the ruling and inking rollers separated from the frame. Fig. 5 is a section of the device of Fig. 3. Figs. 6 and 7 are respectively detail elevations of a clamping washer and a ruling-disk.

This hand-ruling machine consists of the bifurcated integral frame *a*, provided with the rearwardly-extending handle *b*.

A flexible and porous inking-roller *i* is jour-

naled between the arms of the bifurcated frame near the closed end thereof, and this roller consists of a central shaft and a cylinder of felt or the like absorbent material upon the same.

The ruling device proper consists of a cylinder *c*, journaled in the outer ends of the arms of the frame and provided with a stop *g* at one end and a screw nut or washer *d* at the other end, and on the cylinder are removably and rigidly clamped by means of said nut a series of ruling disks or rings *e*, all of the same diameter, and provided with a central opening to snugly fit and slide upon the cylinder, and the disks are of such diameter that when upon the cylinder their peripheries will bear against the periphery of the inking-roller with considerable pressure, so that when rotated they will cause said inking-roller to rotate. The marking peripheries of the disks are of such width as to produce lines of the required heaviness. The marking-disks are held the desired distance apart by means of the loose interposed washers *f*; hence, if it is desired to increase or decrease the number of lines ruled or the distance between the lines, one of the arms of the frame is forced slightly out, thereby allowing the ruling-cylinder to fall out. The nut *d* is then removed and the washers and marking-disks slipped off and on until correctly adjusted. They are then clamped in position by the nut and the ruling-cylinder springs back into place.

In Fig. 3 the ruling-cylinder *g* is shown as formed integral with a series of peripheral V-shaped grooves, thereby forming the circular parallel marking-edges or disks *h*.

The operation of the device is obvious. A suitable ink is first placed on the inking-roller, and of course as the marking-cylinder is run over the paper the friction will rotate said cylinder, which in turn will rotate the inking-roller, and sufficient ink from the roller will adhere to the marking edges or peripheries to make a continuous clear line on the paper.

This device is adapted for many uses and fills a long-felt want. It is of great value to book-keepers and others having to rule parallel lines, as the device is cheap and simple and easy to operate and can be used with far greater ease and quickness than a common ruling-pen. The construction of Fig. 3 is of

great particular value for ruling the parallel lines constituting the staff upon which musical notes are written; hence, the invention is of great value to musicians. If an inking-
5 roller wears out, it can be quickly and easily replaced by a perfect one.

What I claim is—

1. A hand device for ruling straight parallel lines, consisting of a single frame composed
10 of a pair of parallel arms connected at their inner ends, and a rearwardly-extending handle, an inking-roller journaled between the inner portions of said arms and having an elastic porous periphery and ruling-cylinder
15 journaled between the outer portions of said arms and having a series of annular parallel projecting ruling-edges constantly bearing against the periphery of the inking-roller and adapted to rotate the same when the ruling-
20 cylinder is rotated, substantially as described.

2. A hand device for ruling parallel lines, consisting of a single frame having a pair of parallel arms, and a rearwardly-extending handle, an inking-cylinder journaled between 25 the inner portions of said arms and having a porous periphery, and a ruling-cylinder journaled between the outer ends of said arms and provided with a series of adjustable separately-removable parallel ruling-disks 30 clamped thereon and constantly bearing against the inking-roller, so as to rotate the same when the ruling-cylinder is rotated, substantially as described.

In testimony that I claim the foregoing as 35 my own I affix my signature in presence of two witnesses.

WILLIAM A. SHAW.
